UNITED STATES PATENT OFFICE.

LOUIS ROSENBAUM, OF NEW YORK, N. Y.

PRESSING-MACHINE.

1,128,520.

Specification of Letters Patent. Patented Feb. 16, 1915.

Application filed October 22, 1914. Serial No. 868,065.

To all whom it may concern:

Be it known that I, LOUIS ROSENBAUM, a citizen of the United States, residing at the city of New York, borough of Manhattan, State of New York, have invented certain new and useful Improvements in Pressing-Machines, of which the following is a specification, reference being had to the accompanying drawings, forming a part 10 thereof, in which—

Figure 1 is a rear elevational view of a pressing-machine embodying my invention; Fig. 2 is a vertical longitudinal sectional view through the same; Fig. 3 is a detail 15 transverse sectional view on the line 3—3, Fig. 2; Fig. 4 is a detail transverse sectional view on the line 4—4, Fig. 2; Fig. 5 is a detail rear elevational view of the spring-housing or casing; Fig. 6 is a fragmentary 20 side elevational view, partly in section, of the lower part of the machine; and Fig. 7 is a plan view on the line 7—7, Fig. 6.

This invention relates to certain new and useful improvements in garment pressing 25 machines, the objects of my present invention being to provide an efficient, powerful, and easily-operated machine of the kind stated of durable preferably all metallic construction, and to improve generally upon 30 machines of the kind described.

With these objects in view, my present invention resides in certain novel features of form, construction, arrangement, and combination of parts, all as will hereinafter 35 be described and afterward pointed out in the claims.

Referring to the accompanying drawings, in which like reference characters refer to like parts throughout the several views. A 40 indicates a suitably preferably all metallic table or frame made up of or including up-standing standards 1—1 and a top 2, each of said standards 1—1 preferably integrally comprising vertically-disposed members or 45 legs 3 and upper and lower horizontally-disposed or cross-members 4 and 5, respectively. Rigidly tying standards 1—1 together at the front of table A, is a horizontally-disposed tie or cross-member 6 having 50 its opposite ends fixed to standards 1—1 adjacent the lower ends of legs 3. At the front of table A, standards 1—1 are each provided preferably integrally with an upwardly presented approximately rectangular extension 7, upon which is preferably

fixed a horizontally-disposed ironing or pressing plate 8, as clearly seen in Figs. 1 and 2.

Suitably fixed to, and extending lengthwise between, standards 1—1 at the rear of table A, as seen clearly in Fig. 1, is an approximately rectangular casting or the like 9 centrally cutaway, as at 10. At the upper and lower sides of its said cutaway portion 10, casting 9 is centrally thickened to provide 60 bearings 11—11 having alining openings or perforations in which loosely and slidably fits an elongated vertically-disposed cylindrical bar 12 having fixed thereto at its lower end a collar, head or enlargement 13 65 preferably flat on its upper face.

14 indicates a member having approximately the shape in side elevation of an inverted L, comprising preferably integrally a relatively short horizontally-disposed tubular arm or portion 15 and a relatively long vertically-disposed arm or portion 16 longitudinally provided on its outer face with a strengthening web 17. On its under or inner side, arm or portion 15 of member 75 14 is provided with an enlargement 18 cut away as at 19 and transversely perforated to loosely receive the upper end-portion of bar 12, as seen clearly in Fig. 2, arm 15 being provided with an alining perforation, 80 as at 20, in which the upper end of bar 12 loosely fits. Disposed within said cut away portion 19 of enlargement 18 and having threaded engagement with bar 12, is a nut 21, whereby member 14, although mounted 85 on bar 12, is permitted to rotatably move relatively to table A, for purposes herein-after appearing, a suitable ball or other anti-friction bearing 22 being preferably 90 interposed between the upper face of nut 21 95 and the under face of arm 15, so that member 14 and its carried parts may rotatably move relatively to table A with little or no friction. At its lower end, arm or portion 16 of member 14 is provided with a forwardly-presented split-collar extension 23 adapted with a coöperating split-collar portion 24 fixed thereto to loosely encircle and thereby engage with bar 12, as seen clearly 100 in Figs. 1 and 2.

Loosely and slidably fitting in horizontally-disposed arm or portion 15 of member 14, is a bar 25 adapted at its outer end to adjustably carry a sad-iron or the like 26 normally out of engagement with pressing- 110

plate 8, but adapted, on the actuation of bar 12 and its carried member 14 out of normal position, as hereinafter more fully appearing, to bear upon or engage with plate 8, as seen in Fig. 2, for pressing or ironing operations, as will be well understood. The bore of arm or portion 15 is preferably reduced adjacent its forward end to provide an annular shoulder or the like, as at 27, 5 against which shoulder a collar 28 fixed on the rear end of bar 25 is adapted to engage to prevent the forward removal of bar 25 and its carried iron 26 from arm 15. Bar 25 being readily longitudinally slidable in arm 15, it will be evident that its carried iron 26 may be easily adjustably moved laterally relatively to plate 8 as may be required for the particular pressing or ironing operations or work being done. It will also be 10 seen that, member 14 being rotatably movable on its carrying or supporting bar 12, the iron 26 may be rotatably moved to one side or the other longitudinally relatively to plate 8 as may also be required in the particular pressing or ironing operations 15 being had.

To releasably secure bar 25 and its carried iron 26 in laterally adjusted positions relatively to plate 8, an enlarged set-screw 30 or the like 29 adapted to impingingly engage with bar 25 is provided on arm 15, as seen clearly in Fig. 2; and that bar 25 may 35 slidably move in arm 15 with little or no friction, suitable balls or other anti-friction bearings 30-31 are suitably arranged and interposed therebetween, as seen clearly in Figs. 2, 3, and 4.

Fixed on the upper side or face of casting 9 and perforated or cut away in its base 40 or bottom to slidably accommodate bar 12, as seen clearly in Fig. 2, is an upstanding-cup-shaped member or the like 32, and surrounding or encircling at its lower end said cup-shaped member 32 and interposed between 45 the upper face of casting 9 and the under face of enlargement 18 of arm 15, is a vertically-movable cylindrical casing or housing 33 open at its lower end and longitudinally slotted, as at 34, to receive and 50 operate with an outwardly-presented guiding-lug or key 35 provided preferably integrally on the outer face of cup-shaped member 32. Arranged in casing or housing 33 and interposed between the upper end thereof and the base or bottom of cup-shaped member 32, as seen clearly in Fig. 2, is a coiled spring or other suitable resilient member 36 adapted to normally yieldingly hold bar 12 with said member 14 and its 55 carried parts in raised or elevated inoperative pressing position relatively to table A and its ironing or pressing-plate 8. To hold spring 36 against rotatory movement relatively to its housing 33, I preferably 60 provide transverse set-screws or the like 37, as

also seen in Fig. 2; and that work or articles on table-top 2 may not accidentally or otherwise interfere with the proper movements of casing or housing 33 in the operations of the machine, an upstanding somewhat arched wall 38 preferably integral with casting 9 is provided there around, as seen clearly in Fig. 1.

Projecting downwardly from, and preferably integral with, the lower side of casting 70 9 is a pair of spaced-apart lugs disposed on opposite sides of bar 12 and having preferably the shape in side elevation seen clearly in Fig. 6, said lugs providing a pair of obliquely downwardly and forwardly presented ears 39-39 and a pair of obliquely downwardly and rearwardly presented ears 40-40. Having its rear end fitting between, and pivotally connected to, said pair of ears 39-39 is a forwardly presented treadle 41 80 85 preferably strengthened on its under side by a longitudinally-extending vertically-disposed web 42 and provided at its forward or free end with a step or foot-receiving flat portion 43. Treadle 41 at its rear end is 90 provided with an obliquely rearwardly and downwardly presented bifurcated extension or cam-member 44 adapted to straddle bar 12, as seen clearly in Fig. 7. Fitting between, and pivotally connected to, said ears 95 40-40 directly in the rear of treadle cam-member 44, is a second cam-member 45 having a bifurcated extension or portion 46 adapted also to straddle bar 12 and to be 100 slidably engaged by co-operating cam-member 44, as seen clearly in Figs. 2 and 6. This cam-member 45, in side elevation, has preferably the shape or form seen in Fig. 6, and at the lower end of its said bifurcated extension 46 is adapted to camwise engage with 105 the upper face of collar 13, whereby treadle 41 is normally held, by tension of spring 36, in the position shown in dotted lines in Fig. 2 and in full lines in Fig. 6. On depressing treadle 41 cam-member 45 will be pivotally 110 moved outwardly and bar 12 and its carried parts consequently lowered, iron 26 being brought, against the tension of spring 36, into operative pressing engagement with plate 8. On releasing treadle 41 the parts, 115 under the pull of spring 36, will be quickly returned to normal position.

Having pivotal connection with, and being disposed on opposite sides of, web 42, is a pair of preferably triangularly shaped 120 members 47, and fulcrumed at its forward end between said members or parts 47, as seen in Figs. 2 and 6, is a rearwardly presented auxiliary cam-actuating member in the form preferably of a lengthwise adjustable bar or rod 48. At its opposite or rear end, rod or bar 48 is longitudinally provided with a bifurcated extension 49 adapted also to straddle bar 12 and on the depression of treadle 41 engage with the forwardly- 125 130

presented ends of cam-extension 46 and thereby increase and quicken the cam-wise depressing pull of cam-member 45 on bar 12 and its carried parts.

5 At its upper end cam-member 45 is provided with an upwardly presented lug or ear 50, in which is threaded an adjustable set-screw or the like 51 adapted, on the depression of treadle 41 and the rearward actuation of cam-member 45 as described, to abut against a downwardly presented lug 52 on casting 9 to limit or regulate the amount of depressive movement of treadle 41 and consequently also of bar 12 and its carried parts.

10 I have found my new machine to be most easy and positive of operation and most efficient in use, the pressure exerted by the iron being so powerful as to quickly and 20 neatly press the heaviest garment or fabric made.

15 I am aware that changes in the form, construction, arrangement, and combination of the several parts of my new machine may be 25 made and substituted for those herein shown and described without departing from the nature and spirit of my invention.

Having thus described my invention, what I claim and desire to secure by Letters Patent is:

30 1. In a pressing-machine of the kind stated, the combination with a table, of means adapted to carry a sad-iron mounted on said table, said means including an elongated headed bar slidably movable relatively to said table, means for yieldingly holding said carrying-means in normal position relatively to said table, a cam-member pivotally mounted on said table and slidably engaging with the head of said bar, a treadle pivotally mounted on said table, and a cam-extension on said treadle adapted to coöperate with said cam-member on the depression of said treadle to slidably actuate 35 said carrying-means against the tension of said holding-means into operative pressing position relatively to said table; substantially as described.

40 2. In a pressing-machine of the kind stated, the combination with a table, of an elongated vertically-disposed headed bar slidably mounted on said table, a sad-iron carrying-member mounted on, and movable with, said bar, resilient means interposed between said member and said table adapted to yieldingly hold said member and said bar in normal position relatively to said table, a cam-member pivotally mounted on said table and slidably engaging with the head of said bar, a treadle pivotally mounted on said table, and a cam-extension on said treadle adapted to coöperate with said cam-member on the depression of said treadle to slidably actuate said bar and its carried 45 parts against the tension of said resilient

means into operative pressing position relatively to said table; substantially as described.

3. In a pressing-machine of the kind stated, the combination with a table, of means adapted to carry a sad-iron mounted on said table, said means including an elongated headed bar slidably movable relatively to said table, means for yieldingly holding said carrying-means in normal position relatively to said table, a cam-member pivotally mounted on said table and slidably engaging with the head of said bar, a treadle pivotally mounted on said table and adapted to coöperate with said cam-member 70 on the depression of said treadle to slidably actuate said carrying-means against the tension of said holding-means into operative pressing position relatively to said table, and an auxiliary cam-engaging member carried by said treadle adapted to increase the actuating pressure on said cam-member on the depression of said treadle; substantially as described.

4. In a pressing-machine of the kind stated, the combination with a table, of means adapted to carry a sad-iron mounted on said table, said means including an elongated bar slidably movable relatively to said table, means for yieldingly holding said carrying means in normal position relatively to said table, a cam-member having engagement with said bar, and means adapted to coöperate with said cam-member to slidably actuate said carrying-means against 90 the tension of said holding-means into operative pressing position relatively to said table, said last-named means including a treadle pivotally mounted on said table and a rod at one end pivotally connected to said 95 treadle and at its other end engaging with said cam-member; substantially as described.

5. In a pressing-machine of the kind stated, the combination with a table, of means adapted to carry a sad-iron mounted on said table, said means including an elongated headed bar slidably removable relatively to said table, means for yieldingly holding said carrying-means in normal position 110 relatively to said table, a cam-member pivotally mounted on said table and slidably engaging with the head of said bar, a treadle pivotally mounted on said table, and means adapted to coöperate with said cam-member on the depression of said treadle to slidably actuate said carrying-means against the tension of said holding-means into operative pressing position relatively to said 115 holding-means, said coöperating means including a cam-extension on said treadle and a rod pivotally connected at one end to said treadle; substantially as described.

6. In a pressing-machine of the kind stated, the combination with a table, of an 120

elongated vertically-disposed headed bar 5
slidably mounted on said table, a sad-iron
carrying-member mounted on, and movable
with, said bar, resilient means interposed
between said member and said table adapted
to yieldingly hold said member and said bar
in normal position relatively to said table, a
cam-member pivotally mounted on said
table and slidably engaging with the head
10 of said bar, a treadle pivotally mounted on
said table, a cam-extension on said treadle
adapted to coöperate with said cam-member
on the depression of said treadle to slidably
actuate said bar and its carried member
15 against the tension of said resilient means
into operative pressing position relatively to
said table, and a rod adapted to increase the
actuating pressure on said cam-member, said
rod engaging at one end with said cam-
member and at its other end having pivotal
20 connection with said treadle; substantially
as described.

7. In a pressing-machine of the kind
stated, the combination with a table, of

means adapted to carry a sad-iron mounted 25
on said table, said means including an elongated
headed bar slidably movable relatively
to said table, means for yieldingly holding
said carrying-means in normal position
30 relatively to said table, a cam-member pivotally
mounted on said table and slidably engaging
with the head of said bar, means adapted
to pivotally move said cam-member to slidably
actuate said carrying-means against the tension
35 of said holding-means into operative pressing
position relatively to said table, a lug on the table and a member
carried by said cam-member adapted to engage
with said lug to limit the pivotal movement
of said cam-member; substantially 40
as described.

In testimony whereof, I have signed my
name to this specification, in the presence of
two subscribing witnesses.

LOUIS ROSENBAUM.
